United States Patent Office

Des. 204,995
Patented June 7, 1966

204,995

MOWER-CRUSHER

Constantine J. Kermes, Lancaster, and Emmett F. Glass,
Akron, Pa., assignors to Sperry Rand Corporation, New
Holland, Pa., a corporation of Delaware

Filed Sept. 13, 1965, Ser. No. 86,994

Term of patent 14 years

(Cl. D40—1)

Fig. 1.

Fig. 3.

Fig. 2.

Fig. 4.

FIG. 1 is a perspective view of a mower-crusher embodying our new design;

FIG. 2 is an elevation as seen from the left of FIG. 1 rotated 180°;

FIG. 3 is an elevation as seen from the right of FIG. 1 rotated 180°;

FIG. 4 is a rear elevation thereof.

The dominant features of our design reside in the portions shown in full lines.

We claim:

The ornamental design for a mower-crusher, as shown and described.
